UNITED STATES PATENT OFFICE.

FRANK T. WAKEFIELD, OF PITTSBURGH, PENNSYLVANIA.

GAME APPARATUS.

1,418,409.

Specification of Letters Patent. Patented June 6, 1922.

Application filed April 10, 1920, Serial No. 372,803. Renewed April 18, 1922. Serial No. 555,238.

To all whom it may concern:

Be it known that I, FRANK T. WAKEFIELD, a citizen of the United States of America, residing at Pittsburgh, in the county of Allegheny and State of Pennsylvania, have invented certain new and useful Improvements in Game Apparatus, of which the following is a specification.

My invention relates to improvements in game apparatus, and more particularly to an apparatus designed for playing what is known as a war game, an object of the invention being to provide a game apparatus in which the play is entirely scientific, and in which game pieces represent and have movements similar to well known implements of warfare so as to give the game a realistic atmosphere.

A further object is to provide a game apparatus which permits the playing of a game for young and old, and which will be neat and attractive in appearance, and comparatively cheap to manufacture.

With these and other objects in view, the invention consists in certain novel features of construction and combinations and arrangements of parts as will be more fully hereinafter described and pointed out in the claims.

30 In the accompanying drawings,

Figure 1 is a plan view of a game board constructed in accordance with the present invention and game pieces arranged in their proper position for starting the play,

35 Figure 2 is a side elevational view of the device shown in Fig. 1,

Figure 3 is an end elevational view thereof,

40 Figure 4 is an elevational view of the game board per se closed for containing the game pieces and the bridge of the apparatus,

Figure 5 is a side elevational view of the bridge,

45 Figure 6 is a vertical sectional view taken substantially upon line VI—VI of Fig. 5,

Figure 7 is a longitudinal sectional view of a modified form of the game board per se,

50 Figure 8 is a fragmentary plan view of the board shown in Fig. 7; and

Figure 9 shows in top plan and elevational views, the crown pieces which are employed for placement upon the game pieces representing infantrymen when the latter reach an opponent's crown or king row.

In the preferred form of construction, the game board per se preferably comprises two

longitudinal half sections 5 and 6 placed in side by side relation and hingedly connected as at 7 so as to permit the sections to be 60 folded as shown in Fig. 4 like ordinary checker boards when not in use, the sections 5 and 6, when folded, presenting a receptacle for containing the game pieces and bridge of the present apparatus.

65 The game board, when opened, is preferably of oblong formation and has, painted or otherwise provided on its face, two like checkered sections 8 and 9, arranged like an ordinary checker board, i. e., the two sections 8 and 9 together, if unseparated, would present a parallelogram, and each section is divided into an equal number of square spaces. The two checkered sections 8 and 9 are separated by two transverse rows of 70 square spaces 10 and 11 which begin one row inwardly from each side of the board, thus leaving central side unused or blank spaces 12. Every other one of the square spaces is colored dark and they are arranged 75 so that the dark colors meet each other diagonally as is the case in checker boards.

80 A plate 13 which is preferably transparent, is supported a suitable distance above the game board by means of substantially inverted U-shaped supporting brackets 14 which are arranged at the ends of the plate 13 and transversely of the latter, the vertical legs of the brackets 14 having their lower ends removably frictionally seated in 85 sockets 15 provided in the game board, and the leg connecting members of the brackets being flatly fastened against the under side of the plate 13 by means of screws 16 or the like. The plate 13 is of such form and 90 is so arranged as to substantially cover the two rows of square spaces 10 and 11 which connect the checkered sections 8 and 9, and said plate 13 is provided with marks 17 immediately above each colored square in the 95 rows 10 and 11 for visibly indicating possible landing places for such of the game pieces as cannot pass under the plate 13.

100 Also, the brackets 14 are engaged with the board at opposite sides of the hinge connection 7 between the two board sections 5 and 6 so that, when the plate 13 is operatively disposed, the board is held perfectly flat and prevented from accidental folding.

105 As is the case with checkers, the present game is adapted to be played by two players each having a set of game pieces corresponding in number but distinguished by contrasting colors, and the game pieces are adapted 110

to be placed in predetermined positions upon the board by each player. As shown in Fig. 1 there are four colored square spaces in each transverse row of each checkered section 8 and 9, and a game piece 18 representing a "tank", rests upon each colored space of the row of both checkered sections 8 and 9 nearest the plate 13. Game pieces 19 representing infantrymen are similarly arranged upon the next row of each checkered section, while further game pieces 20 representing aeroplanes are similarly placed on the third row of each checkered section. All of these pieces rest upon the game board 15 in a horizontal plane below the plane of the plate 13 so that the atmosphere presented is that of implements of warfare positioned in trenches and adapted to be moved upwardly upon the plate 13 for simulating the 20 well known act of "going over the top". Two further game pieces 21 are provided for each player for placement in the last or crown row of the checkered sections, and these pieces are formed to represent 25 submarines and are placed by each player in the second and third colored square spaces from the right of each player. These submarine game pieces are of such size as to pass beneath the plate 13 and, when said 30 pieces are at a position of rest under said plate, the same are in a safety zone and have the appearance of being submerged. Thus, it will be seen that the present apparatus involves construction and forms of game 35 pieces of such nature that when the game is played the same gives a realistic war atmosphere.

When playing of the game commences, the 40 movement is exactly as in checkers with respect to the pieces 18 and 19, there being one move at a time, and the players taking turns alternately. Certain of the marks 17 upon the plate 13 are provided with distinguishing indications 22 for indicating the 45 sole places where the aeroplane pieces 20 may land upon the plate 13, and the aeroplane game pieces are restricted in movement from their initial point of rest as shown in Fig. 1 to either one of the two 50 distinguished marks 17 upon the plate 13 nearest the opponent's game pieces. The only next possible move of the pieces 20 is from the plate 13 to the crown row of the opponent.

55 The submarine game pieces 21 have movement only in a forward rectilinear direction from one black space to another, one move being permitted for these pieces at a time. The tank pieces 18 and infantry pieces 60 19 are moved diagonally as in checkers one space at a time, and captures are effected by these pieces by leaping over the enemy diagonally into the vacant square beyond, the captured pieces being removed from the 65 board. The pieces 18 and 19 may move di-

agonally one space at a time upon any of the marks 17 of the plate 13, and when any of the game pieces have successfully moved to the crown row of the enemy, a score is counted, one point being given for an aeroplane, two for a tank, three for an infantryman, four for a submarine, and the infantryman being crowned at such time by a piece such as shown in Fig. 9 involving a disk 23 provided with a radial slot 24 so that said disk may rest upon the base 25 of the piece 19 encircling the shank 26 of the latter. At the start of the game the tank pieces 18 have the privilege of moving in either direction like a king in checkers, while the infantry 80 men pieces 19, are restricted to move toward the enemy until crowned, when they also may move in either direction. It is an object of the game to move the pieces to the crown row of the enemy, then back to 85 the home crown row of the player of the piece, and then again to the crown row of the enemy as much as possible in view of the fact that every time this is done the player scores a point or points. It will thus be 90 seen that the present game embodies not only the principle of elimination of pieces as in checkers, but also the scoring of points. Play may be stopped after any predetermined number of games and the player having the largest number of points is considered as winning.

It often happens in the course of playing the present game, that one player corners the 100 opposing player's pieces so that said opposing player is unable to make a move. In this case the player effecting a cornering scores five points. Further, the bridge or plate 13 is made transparent so that the 105 submarine pieces will be clearly in view of both players when at rest under the plate 13.

If desired, the game board of the present apparatus may be of sectional construction so as to enable removal of the central portion of the same which carries two rows of squares 10 and 11 for permitting the two 110 checkered sections 8 and 9 to be placed in contiguous relation so that the ordinary game of checkers may be played thereon, it being noted, as herein before mentioned, 115 that each checkered section 8 and 9 constitutes substantially exactly one-half of an ordinary checker board. As shown in Figs. 7 and 8, this may be done by forming the game board in three transverse sections 27, 120 28 and 29, the faces of the sections 27 and 29 carrying the checkered sections 8 and 9, and the face of the section 28 carrying the two rows of spaces 10 and 11. Any suitable means may be provided for detachably connecting the board sections 27, 28 and 125 29 in their proper relation and for connecting the board sections 27 and 29 when the board section 28 is removed. As shown in Fig. 8, this may be accomplished by pro- 130

viding dowel pins 30 on the edges of the board sections 28 and 29 for removable reception within sockets 31 provided in the adjacent edges of the board sections 27 and 5 28 after the manner of the usual table top construction of extension tables having removable leaves. In the form of the invention shown in Figs. 7 and 8, the removable central section 28 of the game board carries 10 the transparent plate 13 in the same manner as the same is carried in connection with the form of board shown in Figs. 1 to 4 inclusive.

It is believed that the construction and 15 manner of use of the present invention will be readily understood by those skilled in the art, and it will be seen that I have provided a simple but enticing game which will furnish genuine pleasure to those playing 20 the same whether young or old.

I do not limit myself to the precise way 25 of marking and laying out the game board as above described, nor to the particular way of playing the game, although that described 30 is believed to be preferable after considerable experimenting and study.

What I claim as new is:—

1. A game apparatus comprising a game 35 board having on its face two similar checkered sections connected by transverse rows of checkered spaces defining a safety zone on the face of the board for certain game pieces of the apparatus, and means providing elevated landing places for other game pieces 40 of the apparatus at said safety zone.

2. A game apparatus comprising a game 45 board having on its face two similar checkered sections connected by transverse rows of checkered spaces defining a safety zone for certain game pieces of the apparatus, a plate supported above said transverse rows of spaces beneath which said certain game pieces are adapted to be moved in playing the game and having indicating marks thereon for defining resting places on the plate for other game pieces of the apparatus.

3. A game apparatus comprising a game 50 board having on its face two similar checkered sections connected by transverse rows of checkered spaces defining a safety zone for certain game pieces of the apparatus, a plate supported above said two transverse rows of spaces beneath which said certain game pieces are adapted to be moved in playing the game and having indicating marks thereon for defining resting places on the plate for other game pieces of the apparatus, said plate having distinguishing indications 55 at certain of said indicating marks for indicating restricting places of rest upon the plate for certain of said other game pieces.

4. A game apparatus comprising a game 60 board having on its face two similar checkered sections connected by transverse rows of checkered spaces defining a safety zone for

certain game pieces of the apparatus, a plate supported above said two transverse rows of spaces beneath which said certain game pieces are adapted to be moved in playing the game and having indicating marks 70 thereon for defining resting places on the plate for other game pieces of the apparatus, said game board comprising two longitudinal hingedly connected sections retained in open relation by said plate. 75

5. A game apparatus comprising a game board having a checkered face, and a plate supported transversely above the central portion of the game board beneath which certain game pieces of the apparatus are 80 adapted to be moved in playing the game, said plate having positions of rest marked thereon for the remaining game pieces of the apparatus.

6. A game apparatus comprising a game 85 board having a checkered face, a transparent plate supported transversely above the central portion of the board, game pieces constructed to be moved on said checkered face and under said plate with a safety rest 90 when beneath said plate, and other game pieces constructed so as to be incapable of moving under said plate and adapted to be moved on the checkered face past said plate.

7. A game apparatus comprising a game 95 board having a checkered face, a transparent plate supported transversely above the central portion of the board, the board being provided with unused spaces at the opposite ends of said plate, and the plate having 100 marks thereon for indicating positions of rest for certain game pieces of the apparatus.

8. A game apparatus comprising a game 105 board having a checkered face, a transparent plate supported transversely above the central portion of the board, the board being provided with unused space at the opposite ends of said plate, and the plate having marks thereon for indicating positions of rest for certain game pieces of the apparatus, 110 the marks on the plate being directly above resting places on the face of the game board.

9. A game apparatus comprising a game 115 board formed of two end and an intermediate removable section, the two end sections each having checkered faces corresponding to one-half of the checkered face of a checker board, and the intermediate section having a plurality of rows of square spaces defining 120 a safety zone for certain game pieces of the apparatus, means to connect the two end sections of the game board when the intermediate section is removed, and a plate carried by and supported above the intermediate 125 section and provided with indicating marks representing points of rest for certain other game pieces of the apparatus.

In testimony whereof I affix my signature.
FRANK T. WAKEFIELD.
